PAIR OF SUNGLASSES

Manuel Nadel, Lido Beach, N.Y., assignor to Comptone Company, Ltd., New York, N.Y., a corporation of New York

Filed Apr. 7, 1964, Ser. No. 79,382

Term of patent 7 years

(Cl. D57—1)

FIG. 1 is a front perspective view of a pair of sunglasses showing my new design;

FIG. 2 is a left side elevational view thereof; and

FIG. 3 is a rear perspective view thereof.

I claim:

The ornamental design for a pair of sunglasses, substantially as shown.
